CLAIM

Sep. 30, 2016 (JP) 2016-021362
Sep. 30, 2016 (JP) 2016-021363

The ornamental design for a semiconductor device, as shown and described.

DESCRIPTION

(51) LOC (11) Cl. **13-03**

FIG. 1 is a front, bottom, and right side perspective view of a semiconductor device showing our new design;
FIG. 2 is a rear, top, and left side perspective view thereof;
FIG. 3 is a front elevational view thereof;
FIG. 4 is a rear elevational view thereof;
FIG. 5 is a top plan view thereof;
FIG. 6 is a bottom plan view thereof; and,
FIG. 7 is a right side view thereof, the left side view being a mirror image of FIG. 7.
